APPARATUS FOR THE STERILIZATION AND
STERILE FILLING OF VESSELS AND THE
LIKE IN ONE CONTINUOUS WORKING
PROCESSFriedrich Stegemann, Bad Kreuznach, Germany,
assignor to Seitz-Werke G. m. b. H., Kreuz-
nach, Germany, a firmApplication July 3, 1933, Serial No. 678,944
In Germany July 14, 1932

17 Claims. (Cl. 226—110)

The present invention relates to an apparatus for the sterilization and sterile filling of vessels and the like in one continuous working process. An apparatus or device of this kind is described in the U. S. patent application Ser. No. 541,499, filed June 1, 1931 and the main object of the present invention is to further improve such apparatus.

According to the above named application vessels, barrels, casks and the like are sterilized and sterile filled in one continuous procedure without separating the filling member from the cask or the like to be filled. The treatment consists in sterilizing by means of a disinfectant, scavenging by means of a sterile gas, thereby producing a counter-pressure suitable for the filling process, and filling the cask with the liquid in question, for instance with beer, wine or the like. The commencement and the termination of the sterilizing process and the commencement of the scavenging process are controlled automatically as soon as the filling member has been introduced into the cask, whereas the beginning of the filling operation and consequently the interruption of the scavenging preferably is controlled manually.

When the inlet valve for the fluid is operated by hand care must be taken not to stop the scavenging procedure as long as injurious remainders of the disinfectant still are present in the cask. In order to avoid such occurrences under all circumstances the inlet valve of the apparatus is according to the present invention equipped with a timed locking device or cooperates with an optical or acoustic signal device, which indicates the end of the scavenging operation.

The said timed signal devices or the timed devices used for locking the filling member for a definite period and for subsequently opening same may of course be of any suitable design. However, I prefer to control the operation of the locking or signal device by means of a mechanism comprising a cylinder and an appertaining piston. The cylinder or the piston releases and actuates the locking device or actuates the signal device and when the filling member is lowered into the cask to be filled the cylinder or piston partakes in the movement, whereby a spring is tensioned, which subsequently returns the cylinder or piston to its original position. This return movement is counter-acted by a brake fluid. The release of the locking device or the signal device takes place as soon as the cylinder or piston has reached its original position, i. e. after the elapse of a predetermined period.

The locking or signal device may of course also be operated by means of a control mechanism which is driven by a spring or a dead weight. Also a sand glass may be used as control device. Another control mechanism consists of two communicating receptacles one of which is filled with a suitable medium. When this medium is allowed to flow into the other receptacle the receptacles will finally tilt over, and this tilting movement may be utilized for tripping the locking device or the signal device.

A locking device and a signal device can be used together in the same apparatus. The improved device is illustrated diagrammatically and by way of example on the accompanying drawing, which shows a sterilizing and filling device for beer barrels and the like in which a tensioned spring returns a piston or a piston cylinder to its normal position and thereby actuates a locking device or a signal.

Fig. 1 is an axial section on line I—I of Fig. 2 showing the locking device in locking position.

Fig. 2 is a lateral elevational view of the same apparatus. Also in this figure the locking device is shown in locking position.

Fig. 3 shows the locking device in released state.

Fig. 4 is a sectional view taken on line IV—IV of Fig. 1.

Fig. 5 is an enlarged sectional view on line V—V of Fig. 1.

Fig. 6 is a side view showing a device for preventing premature opening of the filling valve.

Figs. 7 to 9 are side views showing the signal means in which the switch member is shown in different positions.

The filling device comprises a cylinder 100 of which only the lower part is shown. A piston 101 enclosed in the cylinder 100 can be lifted by means of compressed air. The compressed air is introduced through a tube 102 and through a bore 103 in the bottom 104 of the cylinder. By means of a valve 105 and a lever 106 the bore may be brought into communication with the tube 102 or with an escape opening (not shown).

107 denotes the piston rod the upper end of which is fixed in the piston 101. To the lower end of the piston rod an arm 108 is attached the movements of which are guided by means of sleeves 109 or the like which cooperate with vertical guide tubes 110 and 111. The upper ends of these tubes are fixed to the bottom of the cylinder 100. The cylinder bottom is as usual equipped with a stuffing box through which the piston rod is passed.

Two cheeks 112 are connected to the arm 108 by casting and the lower ends of these cheeks are

interconnected by means of a cover 113 which is formed with an internal thread. Into this cover the so-called filling head 114 is threaded and in this filling head the filling tube 115 is fixed. The 5 filling head 114 has a lateral lug 116 through which the liquid to be conveyed into the cask or other vessel is supplied in known manner from a container located on a higher level. At the lower end of the filling tube 115 an abutment member 10 117 is arranged and this member is provided with a conical closing valve 118. This valve body is fixed to and operated by a tube 119, which by means of a rubber diaphragm 120 is lifted by the pressure of the liquid when the exposed area of 15 the diaphragm is larger than that of the valve body 118. (See Fig. 1.) In order that the said valve may be opened against the pressure of the liquid the tube 119 is passed through the cover 113 and is connected with a valve head 20 (Fig. 5), the purpose of which will be fully described hereinafter, and with a closing head 122 which cooperates with a cam member 123. This cam member is located on a bolt 124 and is operated by a lever 125 or a projecting finger 126 on 25 this lever. When the lever 125 is depressed the valve 118 is opened.

The bung hole of the cask to be filled is closed by means of the so-called pressing head 127, which is fixed to a rod 128. This rod is guided in 30 the lower cylinder cover 104 and its upper end carries an additional dead weight 129 in order that the pressing head may rest with sufficient pressure on the bung hole of the cask. The head 127 is lifted by means of the member 117 when the 35 filling tube 115 is raised. (See Fig. 1.)

When a cask is to be sterilized the disinfecting agent is introduced through the tube 119. For this purpose the valve head 121 is provided, the interior of which through a bore 131 may be 40 connected with the tube 119 and through another bore may be connected with the tube 132 through which the disinfecting agent is supplied. The admission of the disinfecting agent is controlled by a diaphragm valve 133, which is operated by means of a two-armed lever 134 in a manner 45 which will be detailedly described hereinafter.

The remainder of the disinfecting agent is expelled from the cask by scavenging same with a sterile gas, which also is introduced through the tube 119. For this purpose the valve head 121 is 50 connected with a tube 135 which is controlled by means of a valve 136 the valve body of which is equipped with a fork-shaped lever 137. When the valve 136 is open the scavenging air will flow into the cask through the tube 119 and will leave the cask through the tubes 139 or 140, which are guided in the tubes 110 and 111 respectively in the manner of telescope tubes. The control device, (which will be detailedly described herein- 55 after) is arranged in such a manner, that the scavenging gas through the tubes 119 and 110 and through the valve 141 is let out into the open air or into a gas purifier (not shown). The valve 141 is, like the valves 133 and 136, automatically 60 controlled. The control is exerted by means of a lever 143 which cooperates with the valve rod 142. Moreover, in conduit 110 or on another suitable place a throttle device is arranged, which during the scavenging produces the counter-pressure 65 needed during the filling procedure.

When the valve 141 is closed at the beginning of the filling procedure proper the air escapes through the tubes 140 and 111 and passes into the main beer container in case the apparatus is 70

connected with a stable-pressure beer filling plant.

The individual valves which are not actuated by means of the lever 125 and the cam 123 are operated automatically by suitably formed stops or abutments during the downward stroke of the filling device. The stops are located on sleeves 144 and 145 of which 144 is adjustably arranged on the rod 128, whereas 145 is fixed to the tubes 110 and 111. The valve 133 is controlled by an 10 upwardly yielding lever 146, which is located on the sleeve 144, and by a roller 147 on the sleeve 145. The downward movement of the valve 122 and the two-armed lever 134 will continue also after the pressing head 127 has been brought 15 into contact with the cask. When the lever 134 is operated the valve is opened and shortly before the termination of the downward stroke of the filling tube said lever 134 will contact with the roller 147 whereby the valve again is closed. 20 On account of the resiliency of the lever 146 the valve 133 is not opened when the filling tube is lifted.

The valve 136 is operated by a projection 148 which is formed on the sleeve 145. When the 25 projection 148 is caught by the fork-shaped lever 137 the valve is opened. The abutments or projections 147 and 148 are lying on different levels and the distance between these members is so dimensioned, that the valve 133 is closed before 30 the valve 136 is opened. When the filling tube is raised the valve 136 is again closed automatically.

The valve 118 can only be opened by the cam 123 when the locking device is in released i. e. 35 inoperative state. The locking device consists of a cylinder 150 which is filled with oil and in which a piston 151 with a piston rod 152 and a spring 153 are located. The piston rod is pivotally arranged on a pin 154 which is carried by 40 a projecting part of the cylinder cover 104. The cylinder has a projecting part 155 in which a longitudinal hole 156 is formed and the cylinder is fixed to a bolt 157 in a lever 158 which is pivotally arranged on the sleeve 145. The lever 158 is 45 equipped with a projecting part 159 and with a segmental member 160. The sleeve 145 also serves as a bearing for a second two-armed lever 161, the one arm of which lies in the path of the segmental member 160 and the other arm of 50 which lies in the path of the projection 126. In the position shown in Fig. 2 movements of the lever 125 are prevented, since one arm of the lever 161 is arrested by the stop 126 and the other arm of said lever is arrested by the segmental 55 member 160 on the lever 158.

In Fig. 2 the locking device is shown in tensioned state i. e. in locking position. The locking device is tensioned during the downward stroke of the filling tube by means of a roller 60 162, which is arranged on the arm 103. A denotes the original position of the roller and B denotes the position taken up by the roller when the pressing head contacts with the cask. When the lever 158 is still in the position shown in Fig. 65 3 the roller 162 continues its downward movement and strikes against the projecting part 159 which is turned downward. Hereby the cylinder 150 is moved downward whereby simultaneously the spring 153 is tensioned. The oil in 70 the cylinder is for instance through a by-pass conduit 163 conveyed into the lower part of the cylinder. During the continued downward movement the roller 162 again releases the lever 158 and the cylinder 150 and consequently also the 75

lever 158 are forced slowly upward by the pressure of the spring 153. The velocity of this movement may be regulated at will by altering the cross-sectional area of the by-pass conduit 163. 5 Finally the projecting part 159 is brought into the position shown in Fig. 3. The two-armed lever 161 is released and the valve 118 may now be opened by actuating the lever 125 by hand. In Fig. 3 the open position of the lever 125 is indicated in dotted lines.

When the filling tube moves upward and the projection 126 strikes against a roller 164 on the sleeve 144 the valve 118 is again closed automatically. The distance between this roller and the 15 lowermost position of the projection 126 is so dimensioned, that the cask is totally filled before the supply is stopped.

Fig. 6 shows a device for preventing a premature opening of the filling valve, which device is controlled by means of a cylinder. During the 20 downward stroke of the filling member, the lever 158 takes the cylinder 150 along with it and the oil in same is forced under the piston 151. The spring 153 moves again the cylinder 150 upward 25 whereby the latter takes the lever 158 along with it. At the end of its movement the lever abuts against a contact 165 whereby a circuit is closed and an incandescent lamp is ignited or a bell, a loudspeaker or the like is operated to show the 30 beer drawer the proper moment for opening the filling valve.

According to Figs. 7-9 the signal is released by a medium flowing from one container into another one. The switch member which is pivotally 35 arranged on the stationary bolt 168 takes up the position shown in Fig. 9 when the filling member is in its upper position. During the downward stroke of the filling member the roller 162 strikes against the switch member 167, 167a 40 which consists of two vessels interconnected by a narrow bore and which is turned on its pivot into the position shown in Fig. 7. The switch is forced past the yielding locking finger 173 and comes to rest with its upper end resting against 45 the upper surface of said finger. One of these vessels (according to Fig. 2 the vessel 167a) is filled with a liquid or with fine sand or the like. This medium will flow through the bore into the vessel 167. After a period of predetermined 50 length, so much sand will have flowed into the vessel 167, that the switch body is turned into a substantially vertical position (Fig. 8) in which it is pressed against a contact 169 and the circuit of the lamp 166 or another signal-giving 55 device is closed. During the upward stroke of the filling member the roller 170 impacts with the lever 171 (Fig. 8) and turns the switch into the position shown in Fig. 9, whereby the vessel 167a is forced past the yielding locking finger 60 172 into its position of rest.

While I have described my invention as embodied in concrete form and as operating in a specific manner in accordance with the provisions of the patent statutes, it should be understood that I do not limit my invention thereto since various modifications thereof will suggest themselves to those skilled in the art without departing from the spirit of my invention the scope of which is set forth in the annexed claims.

70 I claim:—

1. In an apparatus for the sterilization and the sterile filling of vessels and the like in one continuous procedure, in combination, a reciprocable filling member comprising a valve body 75 and a hollow valve stem, said valve stem being

also adapted to lead a sterilization agent and subsequently a scavenging agent into the vessels to be filled, and a device adapted to be set by the filling member during its downward stroke and to release the valve at a predetermined moment. 5

2. In an apparatus for the sterilization and the sterile filling of vessels and the like in one continuous procedure, in combination, a reciprocable filling member comprising a valve body and a hollow valve stem, said valve stem being also adapted to lead a sterilization agent and subsequently a scavenging agent into the vessels to be filled, and a locking device adapted to be set by the filling member during its downward stroke and to release the valve at a predetermined moment. 15

3. In an apparatus for the sterilization and the sterile filling of vessels and the like in one continuous procedure, in combination, a reciprocable filling member comprising a valve body and a hollow valve stem, said valve stem being also adapted to lead a sterilization agent and subsequently a scavenging agent into the vessels to be filled, and a timed locking device adapted to be set by the filling member during its 20 downward stroke and to release the valve at a predetermined moment. 25

4. In an apparatus for the sterilization and the sterile filling of vessels and the like in one continuous procedure, in combination, a reciprocable filling member comprising a valve body and a hollow valve stem, said valve stem being also adapted to lead a sterilization agent and subsequently a scavenging agent into the vessels to be filled, and a signal device adapted to be set 30 by the filling member during its downward stroke and to indicate the correct moment for opening said valve. 35

5. In an apparatus for the sterilization and the sterile filling of vessels and the like in one continuous procedure, in combination, a reciprocable filling member comprising a valve body and a hollow valve stem, said valve stem being also adapted to lead a sterilization agent and subsequently a scavenging agent into the vessels to 40 be filled, and a timed signal device adapted to be set by the filling member during its downward stroke and to indicate the correct moment for opening said valve. 45

6. In an apparatus for the sterilization and the sterile filling of vessels and the like in one continuous procedure, in combination, a reciprocable filling member comprising a valve body and a hollow valve stem, said valve stem being also adapted to lead a sterilization agent and subsequently a scavenging agent into the vessels to be filled, and an optical signal device adapted to be set by the filling member during its downward stroke and to indicate the correct moment for opening said valve. 55 60

7. In an apparatus for the sterilization and the sterile filling of vessels and the like in one continuous procedure, in combination, a reciprocable filling member comprising a valve body and a hollow valve stem, said valve stem being also adapted to lead a sterilization agent and subsequently a scavenging agent into the vessels to be filled, and an acoustic signal device adapted to be set by the filling member during its downward stroke and to indicate the correct moment 70 for opening said valve. 75

8. In an apparatus for the sterilization and the sterile filling of vessels and the like in one continuous procedure, in combination, a reciprocable filling member, a filling valve in same

and a locking device comprising a cylinder, a piston in said cylinder, and a working medium in said cylinder, and being adapted to be set by the filling member during its downward stroke and to release the filling valve at a predetermined moment.

5 9. In an apparatus for the sterilization and the sterile filling of vessels and the like in one continuous procedure, in combination, a reciprocable filling member, a filling valve in same and a control device comprising a cylinder, a piston in said cylinder, and a working medium in said cylinder and being adapted to be set by the filling member during its downward stroke and 10 to operate a signal device at a predetermined moment.

15 10. In an apparatus for the sterilization and the sterile filling of vessels and the like in one continuous procedure, in combination, a reciprocable filling member comprising a valve body and a hollow valve stem said valve stem being also adapted to lead a sterilization agent and subsequently a scavenging agent into the vessels to be filled, and a control device comprising a 20 spring-actuated driving mechanism and being adapted to be set by the filling member during its downward stroke and to release the valve at a predetermined moment.

25 11. In an apparatus for the sterilization and the sterile filling of vessels and the like in one continuous procedure, in combination, a reciprocable filling member comprising a filling valve in same and a control device comprising two containers which perform a tilting movement when a fluid is allowed to flow from one container into the other, said control device being adapted to be set by the filling member during its downward stroke and to close a signal circuit at a predetermined moment.

30 12. An apparatus for the sterilization and the sterile filling of vessels and the like, comprising, in combination, a supply pipe for the liquid, a reciprocable filling member attached to the lower end of said pipe, means for holding said member 35 in immediate contact with the vessel to be filled during the entire filling operation, a valve for supplying a sterilizing agent, a filling valve, a guide and tightening member adapted to be pressed upon the opening of the vessel to be filled, 40 a guide rod movable together with said guide and tightening member, abutment members attached to said rod, for opening and closing the valve for the sterilizing agent during the upward movement of the filling member and a liquid control adapted to be set by the filling member during its downward stroke and to release said filling valve at a predetermined moment.

45 13. An apparatus for the sterilization and the sterile filling of vessels and the like, comprising, in combination, a supply pipe for the liquid, a reciprocable filling member attached to the lower end of said pipe, means for holding said member 50 in immediate contact with the vessel to be filled during the entire filling operation, a valve for supplying a sterilizing agent, a filling valve, a guide and tightening member adapted to be 55 pressed upon the opening of the vessel to be filled,

a guide rod movable together with said guide and tightening member, abutment members attached to said rod, for opening and closing the valve for the sterilizing agent during the upward movement of the filling member and a locking device 60 adapted to be set by the filling member during its downward stroke and to release said filling valve at a predetermined moment.

65 14. An apparatus for the sterilization and the sterile filling of vessels and the like, comprising, in combination, a supply pipe for the liquid, a reciprocable filling member attached to the lower end of said pipe, means for holding said member in immediate contact with the vessel to be filled during the entire filling operation, a valve for supplying a sterilizing agent, a filling valve, a guide and tightening member adapted to be pressed upon the opening of the vessel to be filled, a guide rod movable together with said guide and tightening member, abutment members attached to said rod, for opening and closing the valve for the sterilizing agent during the upward movement of the filling member, and a signal device 70 adapted to be set by the filling member during its downward stroke and to release a signal at a 75 predetermined moment.

80 15. An apparatus for the sterilization and the sterile filling of vessels and the like, comprising, in combination, a supply pipe for the liquid, a reciprocable filling member attached to the lower end of said pipe, means for holding said filling member in immediate contact with the vessel to be filled during the entire filling operation, a valve for supplying a sterilizing agent, a filling valve, a guide and tightening member adapted to be 85 pressed upon the opening of the vessel to be filled, a guide rod movable together with said guide and tightening member, abutment members attached to said rod, for opening and closing the valve for the sterilizing agent during the upward movement of the filling member and a liquid control adapted to be set by the filling member during its downward stroke and to release said filling valve at a 90 predetermined moment.

95 16. In an apparatus for the sterilization and the sterile filling of vessels and the like in one continuous procedure, in combination, a reciprocable filling member comprising a valve body and a hollow valve stem, said valve stem being also adapted to lead a sterilization agent and subsequently a scavenging agent into the vessels to be filled, and automatically operating means for preventing a premature opening of said valve.

100 17. In an apparatus for the sterilization and the sterile filling of vessels and the like in one continuous procedure, in combination, a reciprocable filling member comprising a valve body and a hollow valve stem, said valve stem being also adapted to lead a sterilization agent into the vessels to be filled, a locking device adapted to be set by the filling member during its downward stroke and to release the valve at a predetermined moment, and a signal device also adapted to be set by the filling member during its downward stroke and to indicate the proper moment 105 for opening said valve.

FRIEDRICH STEGEMANN.
